UNITED STATES PATENT OFFICE.

JOHN W. MABIN, OF RED WING, MINNESOTA.

FLAG-HOLDER.

1,258,799.

Specification of Letters Patent. Patented Mar. 12, 1918.

Application filed June 18, 1917. Serial No. 175,450.

To all whom it may concern:

Be it known that I, JOHN W. MABIN, a citizen of the United States, residing at Red Wing, in the county of Goodhue and 5 State of Minnesota, have invented a new and useful Flag-Holder, of which the following is a specification.

It is the object of this invention to provide novel means whereby an arm, carrying 10 a rotatable flag staff, may be swung outwardly and rotated simultaneously to effect an unrolling of a flag on the staff, and to provide means whereby the arm may be swung inwardly to a housed position, the 15 staff being rotated simultaneously to reel the flag on the staff.

It is within the province of the disclosure to improve generally and to enhance the utility of devices of that type to which the 20 present invention appertains.

With the above and other objects in view which will appear as the description proceeds, the invention resides in the combination and arrangement of parts and in the 25 details of construction hereinafter described and claimed, it being understood that changes in the precise embodiment of the invention herein disclosed can be made within the scope of what is claimed, without departing from the spirit of the invention.

In the accompanying drawings:—

Figure 1 shows in front elevation, a portion of a building to which the device forming the subject matter of this application 35 has been applied, parts being shown in section;

Fig. 2 is a cross section on the line 2—2 of Fig. 1;

Fig. 3 is a cross section showing the staff 40 swung outwardly and the flag unrolled;

Fig. 4 is a section on the line 4—4 of Fig. 3;

Fig. 5 is a bottom plan of the structure shown in Fig. 1.

45 In the drawings, the numeral 1 indicates a support which may be part of a porch, the vertical top board of the porch being shown at 2 and the projecting eaves being shown at 3.

50 The numeral 4 denotes a horizontally swinging arm provided at its inner end with an enlarged vertical head 5 having an opening 6 therethrough, through which passes a shaft 7 shown in Fig. 3. The shaft 7 may 55 be a screw, threaded at one end to engage the eaves 3, and having at its other end, an

enlargement 9 which, engaging the head 5 of the arm 4, prevents the arm from sliding downwardly off the shaft 7.

Adjacent its outer end, the arm 4 is provided with a depending bearing 10. The bearing 10 may be made as desired, but as shown it consists of a piece of wire disposed in helical form, the ends of the helix being extended upwardly through the arm 4 and 65 being bent over on the upper surface of the arm as shown at 12.

The numeral 14 denotes a rotatable staff disposed parallel to the arm 4 and journaled in the bearing 10. Secured to the outer end 70 of the staff 14 is a flag 15. The inner end of the staff 14 carries a reduced spindle 16 which may be made of metal, the spindle 16 being journaled in an opening 17 formed in the head 5.

75 Between the bearing 10 and the head 5, the staff 14 is provided with holes 18 through which are extended flexible elements 19 and 20, the flexible elements 19 and 20 having knots 21 or other enlargements at their ends, 80 which prevent the flexible elements from being pulled out of the holes. The flexible elements are wound in opposite directions around the staff 14. The arm 4 is provided on one side with a guide 22, and a guide 23 85 depends from the eaves 3. The flexible element 19 is rove upwardly through the guide 22 and downwardly through the guide 23. The opposite side of the arm 4 is provided with a guide 24. A guide 25 projects forwardly from the vertical top board 2. The flexible element 20 is rove through the guide 24 and through the guide 25. If desired, the lower ends of the flexible elements 19 and 20 90 may be connected as shown at 26 to form a 95 loop.

When the flexible element 19 is drawn upon, the arm 4 is swung on the shaft 7 until the guide 22 on the arm abuts against the guide 23 on the eaves 3. The arm 4 then 100 stands in outwardly projecting position, at right angles to the vertical top board 2. A continued pull on the flexible element 19 will cause a rotation of the shaft 14 in one direction, and an unfurling of the flag 15. 105 Supposing that the arm 4 is the outstanding position above described, the flexible element 20 may be drawn upon, swinging the arm 4 on the shaft 7 until the arm is disposed parallel to the vertical top board 2, beneath the 110 eaves 3. A continued pull on the flexible element 20 will cause a reverse rotation of

the staff 14, the flag 15 being wound on the shaft. When the arm 4 is swung around as above described, beneath the eaves 3, the arm abuts against the guide 25, the arm 4 thus being prevented from striking and marring the vertical top board 2.

Although the invention has been described for use in connection with a part of a porch, it is to be understood that applications other than those shown in the drawings are possible.

If desired, a pin 27 may be mounted in the staff 14 to the rear of the bearing 10, to prevent the staff from sliding outwardly, thereby disengaging the spindle 16 from the opening 17, and a washer 28 may be placed on the shaft 7 between the head 5 and the eaves 3, so that the ends 12 of the bearing 10 will not scrape the eaves.

Having thus described the invention, what is claimed is:—

1. In a device of the class described, a support; an arm mounted to swing on the sup-

port; a staff journaled for rotation on the arm; guides on the support; and flexible elements rove through the guides, the flexible elements being wound in opposite directions around the staff.

2. In a device of the class described, a support; an arm having an enlarged head; a shaft passing through the head and engaging the support; a bearing carried by the arm; a staff journaled in the bearing and having its inner end journaled in the head; a flag carried by the staff; guides on the support; and flexible elements rove through the guides, the flexible elements being wound in opposite directions around the staff.

In testimony that I claim the foregoing as my own, I have hereto affixed my signature in the presence of two witnesses.

JOHN W. MABIN.
